(57) **CLAIM**

The ornamental design for a storage shelf for television receiver, as shown and described.

DESCRIPTION

FIG. 1 is a top front perspective view of a storage shelf for television receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom front perspective view thereof; and,

FIG. 9 is another top front perspective view thereof, showing the storage shelf for television receiver in a state of use in which it is mounted on a television receiver shown in broken lines.

The dashed broken line showing of a television receiver in FIG. 9 illustrates environment that forms no part of the claimed design. The remaining dashed broken lines in the figures depict portions of the storage shelf for television receiver that form no part of the claimed design.

1 Claim, 9 Drawing Sheets
